UNITED STATES PATENT OFFICE

WILLIAM E. URSCHEL, OF VALPARAISO, INDIANA

BERRY-CLEANING DEVICE

Application filed February 27, 1928. Serial No. 257,119.

This invention relates to agricultural implements and more particularly to huckleberry cleaning devices, although the invention may be employed with equal advantage 5 for other purposes.

It contemplates more especially the provision of improved means for effecting the removal of, appendages constituting undesirable growths on crops or other articles 10 without inflicting any injury thereto. It is of particular importance to effect this result without imparting destructive impacts to the articles, since such are quite delicate in texture and not very resistive 15 without destruction to pressure reactions.

Agricultural cleaners of known construction have not proven entirely satisfactory in that delicate crops or articles such as huckleberries generally are injured during 20 the severance of the appendages therefrom, so that the advantages accruing to the use of power operated devices are minimized by the inability of reaping the entire harvest therefrom. It has been found 25 desirable to retain the berries or other articles in a momentary predetermined position. Slight pressure applying means are employed for effecting this function, but with known contrivances these have not 30 proven entirely satisfactory owing to their tendency to crush or otherwise deface the articles beyond usefulness.

It has been found desirable to control the position of the crops or articles within 35 the mechanism in such a manner as to require the least pressure from the pressure applying means which tends to maintain the required position thereof during the operation of severance of the appendages 40 therefrom.

One object of the present invention is to simplify the construction and improve the operation of devices of the character mentioned.

Another object is the provision of instrumentalities for removing the appendages from articles without the manual handling thereof, thereby minimizing the amount of labor entailed in the cleaning of edible 50 articles.

Still another object is the provision of means for tumbling articles to a predetermined position to effect the severance of appendages therefrom.

A further object is to provide means movable in a predetermined path to effect the severance of appendages from articles and the subsequent discharge thereof without interruption of the continuity of operation. 55

A still further object is the provision of means movable through a predetermined path for arranging articles in a predetermined position thereon for severance by instrumentalities movable relative thereto. 60

Still a further object is to provide means movable along a predetermined path in confronting relation with a pressure applying means maintained in suspension for directing articles thereagainst to effect the severance of appendages therefrom by means 65 movable relative thereto. 70

Other objects and advantages will appear from the following description of an illustrative embodiment of the present invention. 75

In the drawings:

Figure 1 is a view in elevation of a device embodying features of the present invention, parts thereof being broken away to clarify the showing. 80

Figure 2 is a fragmentary plan view in section of the device disclosed in Figure 1.

Figure 3 is a sectional view in elevation of the frame standard employed in connection with the device disclosed in Figure 1. 85

Figure 4 is a fragmentary sectional view taken substantially along line IV-IV of Figure 1.

Figure 5 is a fragmentary view of the appendage severing instrumentality. 90

Figure 6 is a detailed view of means employed to position the articles on the plate prior to the severance of the appendages therefrom.

Figure 7 is a fragmentary view of the plate and severing means disposed in confronting relation therewith to effect the severance of the appendages projecting in the path thereof. 95

Figure 8 is a fragmentary view showing 100

the hopper support and adjustment therefor.

Figure 9 is a sectional view in detail disclosing the manner of securing the article receiving disc in position.

Figure 10 is a sectional view taken substantially along line X—X of Figure 4.

Figure 11 is a fragmentary perspective view illustrating means for applying pressure to berries or fruit in the device.

10 The structure selected for illustration comprises a frame 10 elevated to any suitable position by standards 11 integrally or otherwise associated therewith. Cross members 12 span the standards 11, certain of which support spaced bearings 13 (Fig. 4) in aligned relation for receiving a shaft 14 journaled for rotary movement therein.

15 A bevelled gear 15 is secured to one extremity of the shaft 14 to mesh with a correspondingly shaped gear 16 carried by a vertically disposed shaft 17 having the extremity 18 thereof sustained in a vertical bearing 19. The other extremity of the shaft 17 is journaled in a bearing 21 constituting an integral part of a hopper support member 22. The member 22 terminates in a bracket 23 having a recess 24 provided in an angular extension thereof to confront a correspondingly shaped recess 25 provided in the standards 11. A rod 26 of any suitable construction is interposed between the bracket 23 and the standards 11 for reception within the confronting recesses 24 and 25 to effect the support of the cross member 22.

20 A hopper 27 of any suitable construction and configuration, preferably conical, is supported on the cross member 22 by means of upwardly disposed brackets 28 which terminate in proximity to the mouth of the hopper 27 for attachment thereto by suitable fasteners such as rivets 29. In order to effect the vertical adjustment of the hopper 27 with respect to the cleaning instrumentalities to be subsequently described, the brackets 28 are provided with adjusting screws 30 in axial alignment with the recesses 24 thereof for contact with the rod 26. This expedient enables the elevation or 25 descension of the hopper 27 with respect to the standards 11. As shown, the adjusting screw 30 is provided with a lock nut 31 for insuring the retention of the hopper 27 in its adjusted position, since such would otherwise be subject to accidental displacement owing to the vibrations existent in the frame responsive to the operation of the instrumentalities associated therewith.

30 The hopper 27 is provided with a spout 32 communicating with the apex 33 thereof to guide the articles such as huckleberries to cleaning instrumentalities. The cleaning instrumentalities consist in this instance of a disc 34 which is provided with apertures 35 in its periphery to cooperate with suitable

fasteners to effect the attachment thereof to a peripheral member 36. The peripheral member 36 is provided with inclined bores 37 to enable the projection of studs 38 therethrough which are provided with hooks 39 on their extremities for engagement with the apertures 35 on the disc 34. Fasteners such as the nuts 40 of standard construction threadedly engage the shank of the stud 38 to fasten the disc 34 to the peripheral member 36, there being a lock nut 41 adjacent the nut 40 to insure against any possible displacement which would interfere with the function of the parts.

35 As shown, the peripheral member 36 is bolted or otherwise secured to a dished member or bowl 42 by means of the fasteners 43, thereby rotating in unison owing to the fact that the hub 44 thereof is fixedly secured to an eccentric rotor. The eccentric rotor comprises, in this instance, a tubular member 45 having interiorly disposed circular members 46 and 47 which are in peripheral slidable engagement with the extremities thereof. The members 46 and 47 are provided with aligned, eccentrically disposed bores 48 of substantially the diameter of the vertical shaft 17 which projects therethrough for imparting rotary movement thereto. The tubular member 45 has a gear 49 secured to the extremity thereof exteriorly and concentrically of the eccentric 46. Laterally disposed teeth 50 on the peripheral edge thereof engage and mesh with teeth 51 provided on the face of an annular gear 52 secured to cross members 53 which maintain the gear fixed relative to the pinion 50, thereby imparting slow movement to the tubular member 45 owing to the eccentricities 46 and 47 which cause successive engagement thereof with the annular gear 52 (Fig. 10).

40 The dished member or bowl 42 secured thereto for effecting eccentric circular movement of the article receiving disc 34, imparts a slight vibratory movement thereto, and as a consequence the articles such as huckleberries will roll and tumble thereover. As shown, the disc 34 is provided with a series of concentrically arranged radially disposed slots 54 interposed by uniformly spaced slots 55 of double length for effecting the projection of the article appendages therethrough during their tumbling on the surface thereof. In order that the article appendages, such as appear on huckleberries, may be lodged within the slots 54 and 55 at one time or other during the traverse of the disc 34 in less than an entire revolution, means are provided to exert a slight pressure on the article in its passage from the position of supply to the point of discharge.

45 The pressure applying means consists, in this instance, of flexible linked members or chains 56 which bridge concentrically spaced members guide rails 57 and 58 sus-

pended on either side of the slots 54 and 55 so as to superpose the flexible chains 56 thereabove. The chains 56 are suspended in position from concentrically spaced rods 59, in this instance four, maintained in the desired relation by cross-rods 60 secured thereto by any suitable fasteners such as a wire 61. The rods 60 are secured to a plurality of radially disposed brackets 62 suitably supported from the frame 10 in any suitable manner. Linked chains 63 engage the rods 59 to maintain the flexible chains 56 constituting the pressure applying means in the desired confronting relation with the 15 apertured or slotted portion of the article receiving disc 34. The chains 56 are maintained stationary, and apply a slight pressure to the article 64 which pass thereunder so that the appendages 65 thereof will project through the slots 54 and 55 provided in the disc 34. As shown, the chains 56 commence in proximity to the discharge spout 32 so as to enable the disposition of the articles on the disc 34 which rotates to convey the articles within a circular path defined by the guide rails 57 and 58 on either side of the slots 54, beneath the chains 56 which exert a slight pressure thereon to normally effect the contact of the articles 20 with the disc 34. As a consequence, the appendages 65 of the articles 64 will be projected through the slots 54 and 55 (Fig. 6) during the course of movement, this being rendered possible by the eccentric movement 25 of the plate which vibrates sufficiently to roll or tumble the articles thereover.

In order to effect the removal of the appendages from the articles, severing means are provided to cooperate with the plate or disc 34. The severing means consist, in this instance, of a plurality of radially disposed knives 66 which are secured to extensions 67 integrally or otherwise associated therewith for substantially radial disposition 30 from a hub 68. The knives 66 are secured to the hub 68 by means of suitable fasteners such as the rivets 69 for operative connection with an eccentric 70 secured to the vertical shaft 17 for movement in unison therewith. The eccentric 70 has an eccentricity equivalent to eccentrics 46 and 47, so that the knives 66 will move in substantially the same path as the disc 34 to preclude the possibility of any engagement with the peripheral member 36. The shaft 17, however, rotates at a much higher speed than the tubular member 45 owing to the interposition of the gear 49 therebetween, thereby creating relative movement between the knives 66 and the plate 34. The speedily driven knives 66 are in substantially contacting relation with the relatively slower driven disc 34 in the vicinity of the slots 54 and 55 to shear the appendages 65 from the articles 64 disposed or projected therethrough. To this end, the

blades or knives 66 constituting the severing means are inclined with reference to the plane of the disc 34, thereby imparting a shearing action which removes the appendages from the articles without injury or creating undue stresses thereon.

As shown, the eccentric 70 is provided with an extension 71 constituting a counterbalance for the eccentrics 46 and 47 so as to minimize the vibrations to which the parts 75 are subjected as a result of the eccentricity of their movement. In order to avoid injury to the severing means occasioned by the projection of foreign substances through the slots 54 and 55 of the disc 34, a release mechanism is provided to insure the inoperation of the severing instrumentalities 66 on such occasions. The release mechanism consists of an arm 72 secured to the hub 68 of the severing instrumentalities for radial disposition in the path of a stop 73.

The stop 73 is secured to a guide 74 slidably disposed in a correspondingly shaped slot 75 provided in the surface of the extension or counterbalance 71. A rod 76 is 80 mounted on the extension 71 for relative movement with respect to the stop 73 in alignment with the path of possible movement thereof, there being a nut 77 threaded thereto to maintain a tension spring 78 85 thereon in enveloping relation therewith. The spring 78 urges a ring 79 against the stop 73 to yieldably maintain it in position to preclude relative movement between the eccentric 70 and the knives 66. The engagement of the knives, however, with any unseverable foreign substance projecting through the slots 54 and 55, will cause a stress sufficient to compress the spring 78 90 sufficiently to enable the arm 72 to pass the stop 73, thereby avoiding any serious injury to the knives which would otherwise result. During the interim, the foreign substance will either fall through the slots or the attendant may render the instrumentalities 95 inoperative to remove the impediment from the slots 54 and 55.

The feeding of the articles is insured by virtue of a plate 80 having an aperture 81 provided therein of smaller size than the 100 passage 82 constituting the discharge opening of the spout 32. It is to be noted that the plane 80 is provided with a bearing 83 carried by converging arms 84 associated with the plate 80 to receive a vertically disposed rod extension therethrough which terminates in a horizontal rod 85 having another angular disposed end portion 85' disposed parallel to its other extremity. The end extension 85' projects within a bearing 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950

the eccentric 70 to impart circulatory movement to the plate 80 adjacent the discharge mouth 81 of the spout 32.

The movement of the plate 80 promotes the proper feeding of the articles without any tendency of clogging owing to the comparatively large frictional reaction existent between the respective articles such as berries or huckleberries. A slide 90 is provided to close or otherwise regulate the extent of the discharge passage 80 of the spout 32, thereby effecting the measured discharge of articles to the receiving plate 34. A suitable article feed guide 91 constituting an extension of the spout 32 is employed to properly govern the disposition of the articles on the disc 34 in the path of the slots 54 and 55 provided therein.

It is manifest that the position of the knives 66 relative to the disc 34 will govern the shearing action executed to effect the severance of the appendages from the article. In order to compensate for wear and inaccuracies of manufacture, an adjusting screw 92 threadedly projects through the eccentric 70 with the extremity thereof engaging the eccentric 47. This enables the knives 66 to be elevated or lowered with respect to the plate 34 to govern the shearing action thereof by manipulating the adjusting screw 92. A lock nut 93 is provided on the adjusting screw 92 to maintain the position thereof without any possibility of accidental displacement thereof which would impair the effect of the appendage severing knives 66 during the operation thereof.

It will be apparent from the above description that the deposition of berries on the disc 34 will cause the rolling thereof between the guide rails 57 and 58 disposed on either side of the radial slots 54 and 55 to effect the projection of the article appendages therethrough. The rotation of the knives 66 at a speed much greater than that of the disc 34 effects the shearing of the appendages from the body of the article so as to remove all undesirable growths therefrom. The rolling action of the berries occasioned by the eccentric movement of the disc 34, is somewhat retarded by the exertion of a slight downward pressure on the articles by the flexible chains 56 suspended between the guides 57 and 58, thus causing the appendages to project through the slots with the result that they are sheared therefrom owing to the rotation of the knives 66 substantially contacting with the under side of the disc 34.

Various changes may be made in the embodiment of the invention herein specifically described without departing from or sacrificing any of the advantages as defined in the appended claims.

I claim:

1. The combination with means for feed-

ing articles, of an apertured disc, means for eccentrically moving said disc, means suspended above said disc to bear the articles thereagainst so that the appendages thereof will project through the apertures in said disc, a plurality of severing means mounted adjacent said disc, and means for moving said severing means eccentrically and relative to said disc to remove the article appendages. 70

2. The combination with means for feeding articles, of an apertured disc, means for eccentrically rotating said disc, flexible linked means suspended above said disc to bear the articles thereagainst so that the appendages thereof will project through the apertures in said disc, a plurality of severing means mounted adjacent said disc, and means for moving said severing means relative to said disc and at a higher speed than said disc to remove the article appendages. 80

3. The combination with a frame, of a disc associated therewith, there being radially disposed slots in said disc, means for feeding articles to said disc, flexible means suspended above said disc to direct the articles in contact therewith so that the article appendages project through the slots therein, and a plurality of radially disposed blades confronting said disc for movement relative thereto and eccentrically of said frame for severing the article appendages. 90

4. The combination with a frame, of a disc associated therewith, there being radially disposed slots in said disc, means for imparting eccentric rotary slow movement to said disc, means for feeding articles to said disc, flexible means suspended above said disc to direct the articles in contact therewith so that the article appendages project through the slots therein, and means for effecting the severance of the appendages from the articles comprising a rotating knife, a means for moving said knife eccentrically of said frame and in the same path as said disc but at a greater speed. 105

5. The combination with article confining means, an apertured disc, an eccentric for driving said disc in a circular path to impart eccentric movement thereto, means suspended above said disc, means for feeding articles to said disc and beneath said suspended means effective to retain the articles in contact with the disc so that the appendages project through the apertures therein, and eccentrically mounted severing means driven at a greater speed than but in the same path as said disc to remove the appendages from the articles. 115

6. The combination with article confining means, an apertured disc, an eccentric for driving said disc in a circular path to 120

impart horizontally vibratory movement thereto, means suspended above said disc, means for feeding articles to said disc and beneath said suspended means effective to
5 retain the articles in contact with the disc so that the appendages project through the apertures therein, a plurality of radially disposed knives mounted adjacent said disc, and eccentric means for driving said knives
10 relative to said disc to sever the appendages from the articles.

WILLIAM E. URSCHEL.
